LOADER FOR REFUSE COLLECTING TRUCKS

Ernest C. C. Miller, Laurelton, N. Y.

Application November 22, 1948, Serial No. 61,350

3 Claims. (Cl. 214—67)

1

This invention is for a loader and a packer for a refuse collecting truck and is particularly designed for collecting municipal refuse. Municipal refuse comprises usually ashes, large amounts of paper, cardboard, cartons, tin cans, glass containers, boxes, crates, rags, and similar material. Ordinarily, when the body of the truck is filled with such waste material, the actual weight of the refuse in the body of the truck, due to the fact that the material is loosely packed, is considerably less than the truck could carry if the material were packed in more tightly.

One of the objects of the present invention, therefore, is to provide a refuse collecting truck which will condense and pack the load, thereby increasing the weight of the refuse which can be put in a particular truck body, as compared with a load that is not packed and condensed.

Another object of the invention is to provide in a single unitary mechanism a refuse loader that will receive refuse deposited therein and not only load it into the truck, but also, and as part of the loading operation, pack and condense the same, thereby substantially increasing the weight of refuse that can be put into the truck body.

More specifically, the combined loader and packer of my invention comprises a rotary drum, or the like, set into the loading boot which is carried at the lower end of the tailgate, not more than two or three feet above the ground, so that refuse material can be readily dumped into it by a man standing on the ground. This rotary drum is driven by any suitable source of power, either mechanical or hydraulic. The preferred drive is from an hydraulic motor mounted on the outside of the loading boot and directly connected to the drum. An hydraulic drive is simple, strong, and powerful, and in the event that the loader should jam, any resulting excess pressure can readily be taken care of by an overload release valve; thus no parts are broken. Furthermore, with an hydraulic drive, the fluid under pressure can be readily carried to the motor from the pump by flexible pipes which can be bent and placed in any convenient position. A flexible connection is particularly advantageous in carrying the fluid under pressure from the fixed truck body to the movable tailgate around the tailgate pivot.

The general arrangement of the rotary drum in the loading boot, or hopper, and the means for supporting the loading boot and its associated driving means upon the tailgate of a ref-

2

use truck are more specifically described and claimed in my co-pending application S. N. 660,940, filed April 10, 1946, of which the present invention is an improvement.

It is to be observed that the rotary drum of my improved invention mounted in a passageway in the loading boot, or hopper, is provided with a plurality of pivotally supported impellers which, as the drum rotates, are moved toward and away from the surface of the drum, this movement being so controlled that each impeller, cooperating with a wall of the passageway picks up a charge of refuse and pushes it with a rolling and compacting action through the passage and into the truck body. In addition to the compacting action of the drum, each charge of refuse being forced into the truck body from the bottom and under the load already in the truck is under an additional compacting pressure resulting from the weight of the load above it, thus the entire load is packed into a more solid mass than is possible with other types of loaders.

Cooperating with the rotary drum is a scraper which is designed for removing any accumulated refuse material from the surface of the drum. By the time an impeller reaches the scraper it has been moved into a retracted position, in which position the exposed surface of the impeller is contoured to conform to the surface of the drum, with the result that the scraper can perform its function while the surface of the impeller passes by it. This scraper also functions so as to prevent refuse from being forced back into the hopper while the drum is in operation.

The main features of the invention having been thus outlined, further advantages of structure and operation will be described in connection with the accompanying drawings illustrating the preferred embodiment of the invention.

Referring to the drawings, Fig. 1 is a side elevation of the tailgate structure of a refuse collecting truck showing the combined loader and packer of this invention.

Fig. 2 is a broken cross-sectional elevation of the device taken along the line 2—2 of Fig. 1.

Fig. 3 is an enlarged elevation of my improved loader with portions of the supporting plate, hopper and passage wall and end wall of the drum cut away to show the co-operation of the various parts.

Fig. 4 is a cross-sectional elevation taken along the line 4—4 of Fig. 2 to show the operation of the eccentric guideway.

Referring now to the drawings, a refuse truck body is indicated by the reference numeral 5, provided with a wall 6 through which refuse is to be forced into the body. In the embodiment of my invention shown in my co-pending application S. N. 660,940 the truck body is provided with a removable hinged tailgate, at the lower end of which is mounted a hopper containing a loading device.

In the present embodiment the hopper, indicated generally at 7, comprises spaced vertical walls 8 and 9 extending outwardly from the tailgate 6, bottom wall elements 10, 11, and 49, coaming 12, cover 13, and upper outlet passage wall 20. The bottom wall elements 10, 11, and 49 form a continuous surface of which the elements 10 and 11 converge downwardly toward each other and merge at their lower ends in the arcuate element 49. Circular openings 8' and 9' are provided in the side walls 8 and 9, and circular flanges 8a and 9a extend outwardly therefrom. Circular end plate 14, attached to the flange 8a, as by studs 14a, covers the opening in side wall 8, while the end plate 15, attached as by studs 15a to flange 9a, covers the opening in side wall 9. End plates 14 and 15 are provided with central openings to receive shaft 22, which may be supported on bearings 16 and 17 attached, as by studs 16a and 17a, to the respective end plates. End plates 14 and 15 are also provided on the inner surfaces with cam guiding channels, indicated generally at 18 and 19, respectively, the operation which will be hereinafter described.

Positioned on the shaft 22 is a drum-shaped refuse feeding device, indicated generally at 21, which comprises circular end members 23 and 24, fixed on shaft 22, as by keys 23c and 24c, and spaced on the shaft so as to lie within the flanges 8a and 9a, and having a radius slightly less than the said flanges. Gaskets 23b and 24b may be used to seal the space between them, while allowing rotation of the end members 23 and 24 when the shaft 22 turns. A plurality of impellers 25 are supported on pivot pins 26, extending between end elements 23 and 24, for limited rotation about axes parallel to shaft 22, which movement is controlled by cam rollers 28, supported on pivot pins 27 which project through arcuately shaped slots 24a provided in the end elements, to engage the cam guiding channels 18 and 19. Segmental surface elements 29, spaced between the impellers 25, extend between the inner faces of end elements 23 and 24, and it will be noted that the face 25a of each of the impellers is shaped so that when the impeller is in a retracted position it forms an arcuate continuation of the adjacent segmental surface 29. So that the interior of the drum 21 may be kept free from refuse, which would otherwise prevent operation of the device, the rear portions of the impellers are provided with skirts 25b made in the form of a segment of a cylinder concentric with the pivots 26, which bear against gaskets 29b provided in the adjacent forward edges of the elements 29, while the rear edges of the elements 29 may be formed with arcuate lips 29a which bear against the leading edges of impellers 25. As the impellers revolve on pivot pins 26, the faces 25a of the impellers will remove any refuse which may have accumulated between said lips and the working faces of the impellers. Sprocket wheel 30, mounted on one end of shaft 22, is connected by chain drive means 31 to any suitable driving power source, preferably an hydraulic motor 32, which is connected by flexible conduits 33 and 34

to a source of fluid under pressure which may be supplied by pump means operated by the main engine of the truck.

Scraper blade 37, which forms an extension of the upper passage wall 20, is supported on said wall by pivotal connections 36, and its edge 31a bears against the surface of the drum 21. Horizontally disposed shaft 39, supported by bearings 40 and 41 in side walls 8 and 9, is provided at one end with handle 42. Crank arms 43, attached to shaft 39, are pivotally attached at 46 to the upper ends of links 44, the lower ends of which are pivotally connected at 45 to arms 38, attached to scraper blade 37, so that when the handle 42 is moved in a counterclockwise direction the scraper blade will be turned downwardly and away from the surface of drum element 21. Stop bolts 47, threaded into bracket 48, mounted on wall 20 will engage the links 44 to limit the downward movement of handle 42, while the coil spring 49, one end of which is attached to the boss containing bearing 40 and the other end of which is attached to handle 42 under tension, urges the scraper blade 37 upwardly into contact with the drum 21.

In operation, fluid supplied to motor 32 under pressure rotates the drum 21 in the direction shown by the large arrow in Fig. 1 at a speed of between 5 and 8 revolutions per minute. As the drum 21 revolves on the shaft 22 the impellers 25 will be extended or retracted in response to the influence of the cam guideways 18 and 19 on the cam rollers 28. The action of the guideways can best be observed by studying the operation of the guideway 19 shown in Fig. 4. Shaft 22, rotating counterclockwise, carries the entire drum assembly 21 with it, including pivotal mountings 26 supporting the impellers 25 at the leading edges. It will be observed that the portion of the cam guideway at 19a begins at the top and extends counterclockwise in a circular path of substantially constant radius concentric with the axis of rotation of the assembly 21 for approximately one-half revolution, where it merges into a substantially straight portion 19b which steadily approaches the axis of rotation during approximately a one-quarter revolution, where it merges with another substantially straight portion 19c which steadily recedes from the axis of rotation of assembly 21 during approximately another one-quarter revolution until it merges with the circular path 19a. The disposition of these paths is such that when a cam roller 28 is in engagement with the portion 19a the associated impeller will be fully extended as indicated in Fig. 4; when the cam roller engages the portion 19b the associated impeller will begin to recede with respect to segmental portions 29 within the drum assembly 21 as illustrated by the right hand impeller in the same figure, and it will be fully retracted where the paths 19b and 19c merge; when the cam roller enters the portion 19c the associated impeller will begin a movement of extension with respect to the segmental portions 29 as shown by the top impeller in Fig. 4 until it is fully extended when the cam roller enters the path 19a. Guideway 18 is provided with paths 18a, 18b, and 18c, similar respectively to 19a, 19b, and 19c, but of opposite hand.

Refuse which is to be loaded into the truck 5 will be placed in the opening in hopper 7 surrounded by the protective coaming 12, where it falls on the bottom surface 10 and the left side of the rotating drum assembly 21 (as viewed in Fig. 75 4) where the impellers are in their extended

positions. As rotation of the drum assembly takes place the refuse will be forced with a rolling and compacting motion into the continually decreasing space defined by bottom surface 10, segmental portion 29 and face 25a of an impeller 25, thence pushed under the assembly 21 while confined by bottom wall element 49 until it enters the passage defined by bottom wall 11 and top wall 20. Additional amounts of refuse being pushed into this passage will force the load up into the truck body 5, and as the load builds up the weight of the refuse on top will produce a further compacting influence on the refuse below. The function of the scraper 37, as an extension of wall 28, is to prevent refuse being carried back over the drum assembly into the loading end of hopper 7. Scraper 37 must be positioned so that it will bear against the drum assembly at the place where the impellers will be fully retracted. Due to the contouring of faces 25a there will ordinarily be smooth engagement between assembly 21 and scraper 37, but the fact that the scraper is held by the tension of spring 47 allows for a certain amount of unevenness in the surface of the drum assembly 21. Whenever there is a stoppage of flow in the passage leading into the truck, a workman may depress handle 42, rotating shaft 39 to move the scraper away from the drum assembly to permit refuse to be carried back over the drum temporarily to relieve the congestion.

While the preferred embodiment of the invention has been described in detail, it should be understood that the invention should not be limited to these precise details but that it may be carried out in other ways.

I claim:

1. In a refuse collecting truck having a passage leading into the bottom of said truck body, a horizontally trunnioned drum mounted in said passage, the surface of the drum being spaced from the lower wall of the passage and intersecting the upper wall of the passage, said upper wall being disposed in a plane passing below the axis of the drum, said drum having segmental surface elements pivotally mounted at their leading edges, cam means to cause the segmental elements to be retracted while passing adjacent said upper wall and to be extended while passing adjacent the lower wall, whereby refuse will be urged between the drum and the lower wall, rolled and compacted, and forced through said passage into the truck body.

2. In a refuse collecting truck, a hopper having a passage leading into said truck body, the hopper and the passage having downwardly converging bottom walls merging in an arcuate portion, a drum horizontally trunnioned in said hopper and spaced from said bottom walls, said passage having an upper wall extending in a plane disposed below the axis of the drum in a direction to intersect the surface of the drum, segmental elements of the surface of the drum being pivotally mounted to rotate about their leading edges, cam means to cause the segmental elements to be retracted while passing adjacent the upper wall of the passage and to be extended while passing adjacent the spaced walls, whereby refuse in the hopper is rolled and compacted while being moved under the drum and forced into the truck through said passage.
3. In a loader for a refuse collecting truck having an inclined passage leading into the truck body and a horizontally disposed cylindrical feeding and compacting means, said passage having upper and lower surfaces, said cylindrical feeding means being spaced from the lower surface, the upper surface being disposed in a plane lying below the axis of rotation of the feeding means, said upper surface including a hinged portion adapted to engage the surface of the feeding means, said feeding means including a plurality of segmental surface elements mounted for oscillation about parallel axes and adapted to be extended for feeding and compacting refuse in the passage, and retracted for sliding engagement with said hinged portion of the upper surface of the passage.
